UNITED STATES PATENT OFFICE

FREDERICK A. HART, OF NEW BRITAIN, CONNECTICUT, ASSIGNOR TO REMINGTON TYPEWRITER COMPANY, OF ILLION, NEW YORK, A CORPORATION OF NEW YORK

TYPEWRITING MACHINE

Application filed March 4, 1927. Serial No. 172,685.

My invention relates to typewriting machines, and more particularly to work sheet controlling means by which work sheets may be quickly, and successively, introduced and accurately positioned in the machine.

More specifically considered, my invention relates to paper guiding, end stop and holding devices by which work sheets successively introduced rearwardly from the front of and beneath the platen may be quickly and accurately positioned, and whereby one of said sheets may be held against accidental displacement while another sheet is being introduced in position.

15 The main objects of the invention, generally stated, are to provide improved and comparatively simple devices of the character specified, which are in the nature of attachments that may be readily incorporated in 20 existing machines without modifying, or materially modifying, the existing structural features thereof, and which when desired may be readily detached from the machine as a single unit. A further object of my invention is to provide devices of the character specified which are highly efficient in use and with the aid of which work sheets may be readily and accurately positioned under varying 25 conditions of use and to provide against an accidental displacement of one sheet in the machine as another is being introduced into the machine relatively thereto.

To the above and other ends which will hereinafter appear my invention consists in 30 the features of construction, arrangements of parts and combination of devices to be set forth in the following description and particularly pointed out in the appended claims.

In the accompanying drawings wherein 35 like reference characters indicate corresponding parts in the different views:

Figure 1 is a fore and aft vertical sectional view of a typewriting machine equipped with the devices of my invention, the section being taken on the line 1—1 of Fig. 6 and looking in the direction of the arrows at said line.

Figure 2 is a detail fragmentary perspective view of the double paper apron or deflectors beneath the platen.

Figure 3 is a view corresponding in part to Fig. 1 but showing a somewhat different arrangement or adjustment and use of certain of the devices of the present construction.

Figure 4 is a detail, fragmentary, perspective view of one of the holding and guide springs and some of the associated parts.

Figure 5 is a detail view showing the means for adjustably connecting one of the supporting brackets for the paper table in place, the view being in the nature of a fragmentary section taken on the line 5—5 of Fig. 1 and looking in the direction of the arrows at said line.

Figure 6 is a front elevation with parts broken away of the carriage equipped with the devices of my invention.

Figure 7 is an enlarged detail fragmentary perspective view showing in part the adjusting means for the end stop bar and the means for locking the bar in its adjusted position.

Figure 8 is a fore and aft vertical sectional view corresponding in part to Fig. 1, but showing a different position of adjustment of the stop bar 61 and the parts carried thereby and illustrating certain additional devices not shown in the preceding views.

Figure 9 is a detail, fragmentary, front view, partly in section, showing some of the parts represented in Fig. 8.

Figure 10 is a detail, transverse, sectional view taken on the line 10—10 of Fig. 9 and looking in the direction of the arrows at said line.

Figure 11 is an enlarged detail, fragmentary, transverse, sectional view taken on the line 11—11 of Fig. 9 and looking in the direction of the arrows at said line.

The present invention has some of the same general objects in view as the construction disclosed in the application of Cloyd E. Burns filed July 13, 1926, Ser. No. 122,239 (now Patent No. 1,647,854 granted Nov. 1, 1927) and is in the nature of improvements on the construction disclosed in said application.

The devices of the present invention were devised more especially for use in the Rem-

ington front feed billing machines, certain features of which are disclosed in my application Ser. No. 120,403 filed July 3, 1926 (now Patent No. 1,650,351 dated Nov. 22, 1927). While the devices of the present invention are particularly useful in the machine referred to, it should be understood that their use is not restricted to such machine, but that they may be employed in various forms of typewriting and like machines wherever found available.

In the accompanying drawings I have shown only so much of the said Remington machine as is necessary to arrive at an understanding of my invention in its embodiment therein.

Generally stated, the Remington machines above referred to are employed in various kinds of billing operations, where two or more work sheets are to be correlated in the machine and printed at a single operation. However, I do not deem it necessary to describe specifically the many different forms of billing operations in which the said machines may be used. It is sufficient for an understanding of the present invention to describe in general terms one mode of billing that may be successfully carried out with the aid of said machines and perhaps briefly refer to some of the various other methods in connection with which the machines may be employed together with the paper end stop and other devices of my invention.

One method of using the said machine which will be specifically referred to, is its employment, for example, by a public service corporation such, as, say, an electric or gas light company, for simultaneously, or at one writing, making out a bill, making corresponding entries on the ledger sheet carrying the account, and on a record or register sheet which receives the entries written on all of the individual bill and ledger sheets. In the example referred to the register sheet and its accompanying carbon sheet remain in the machine. The ledger sheet which usually requires but a single cross line entry at a time, say, for the month for which the entry is made, may be in the nature of a blank with different vertically ruled columns to be filled in under appropriate printed headings; each cross line of the sheet being ruled off horizontally and given over to a different month, and the entire sheet covering a period of anywhere from, say, eighteen to thirty-six months. Means are provided to enable each ledger sheet to be quickly introduced backwardly from in front of the platen and properly positioned to receive the requisite entries in the line allotted for the month in question without disturbing the previously introduced register sheet. Means also are provided for then quickly entering a bill sheet and accompanying carbon sheet rearwardly into the machine from in front of

the platen, and accurately positioning them in proper correlation with the previously introduced ledger sheet and the printing line. The entries may then be made on a bill sheet and these will be transferred through interposed carbon sheets to the ledger and register sheets. If desired additional entries may be made on the ledger sheet which are not to appear on the bill or register sheet. The bill and ledger sheets and accompanying carbon sheet are then rapidly withdrawn from the machine without disturbing the register sheet, and another ledger sheet and a bill sheet with accompanying carbon sheet may then be quickly introduced as before, and so on.

In the example of the billing operations explained above the end stops and clamping springs of my present invention are intended to coat with the ledger sheet, to quickly and accurately effect a positioning thereof under varying conditions and hold it against accidental displacement from its adjusted position. It should be understood, however, that in other uses of the machine, the said stop devices of my invention will coat with other sheets in a variety of ways, some of which will be hereinafter explained.

With the foregoing general explanation, I will now proceed to briefly describe so much of the said machine as is necessary to arrive at an understanding of my invention in its embodiment therein.

The frame of the machine is of the usual construction and includes a top plate 1 carrying fixed guide rails 2 (only one of which is shown), oppositely grooved to receive cross anti-friction bearing rollers 3. These rollers are also received in oppositely grooved carriage rails 4 at the front and rear of the carriage (the rear carriage rail only being shown), said carriage rails being connected with the end bars 5 of the carriage.

The carriage, which is power driven in the usual manner, is thus supported and mounted to travel from side to side of the machine over the top plate under control of the usual escapement mechanism (not shown), and in some instances under control of the usual tabulator mechanism.

The platen 7 is carried by the platen frame in the usual manner, said platen frame comprising end plates 8 and 9 united by suitable cross bars. The platen frame is connected to the carriage or truck by links 10 in the usual manner, which links ordinarily guide the platen frame in its case shifting movements. The present machine, however, is intended to write only with capital letters or upper case characters and there is therefore, no case shifting movements of the platen and platen frame; the platen frame being firmly held in its upper case position on the carriage, where it will coat with the outermost types 11 on the type bars 12. These type bars

are mounted in a type bar segment in the usual manner to swing upwardly and rearwardly to printing position where they strike against the front face of the platen.

The usual ribbon vibrator mechanism is employed so as to interpose the ribbon in the path of the types 11 at each actuation of a type bar. Only the upper end portion of the ribbon vibrator 13 is shown, it being understood, however, that the vibrator is guided for up and down movement on the type guide 14 in the usual manner.

As in the construction disclosed in my said prior application, there are two curved paper deflectors 15 and 16 employed beneath the platen, one arranged above the other and maintained spaced apart by intermediate spacing members or blocks 17 and 18 located near the ends thereof. Generally speaking, these deflectors beneath the platen conform substantially to the curvature of the latter, or are substantially concentric therewith, and extend substantially throughout the length of the platen. As thus constructed there are two separate channels provided, one of which is the open channel 19 between the two deflectors, and which is bounded at its ends by the spacing members 17 and 18, either or both of which may constitute side edge guides or gages for cooperation with one or both side edges of a work sheet or sheets introduced into the channel 19. The other separated channel 20 is provided between the under surface of the platen and the upper deflector 15. It will be seen that the forward edge of the deflector 16 terminates in advance of the forward edge of the deflector 15. The deflector 16 is continued up at the rear and terminates at 21 at a considerable height above the platen thus forming a paper table. On the other hand, the deflector 15 terminates in the rear of the platen at a much lower point and below the top of the platen, where it is bent to form a loop 22 that surrounds a rod 23 fixedly connected at its ends to the end plates 8 and 9 of the platen frame. In this manner the rigidly united deflectors 15 and 16, together with all of the parts carried thereby, are mounted on the rod 23. The construction is such that the deflector 15, is lightly pressed against the platen, or against the interposed sheets R, R'. In this manner the sheets R, R', are held snugly against the platen and other sheets including the sheet L, intended to be introduced rearwardly into the channel 19 are prevented from entering the channel 20.

In order to facilitate the backward introduction of work sheets into the channel 19 from in front of the platen there is provided in accordance with the invention disclosed in my prior application, a guide, shield, or paper deflector 24 that is movable on the carriage from a substantially horizontally disposed ineffective position, shown in dotted lines in

Fig. 1, to a downwardly and rearwardly inclined effective position, shown in full lines in said figure and vice versa.

The deflector 24 has depending arms 25 at the ends thereof, each of said arms being pivoted at 26 on an end plate 8 or 9 of the platen frame. In this manner the deflector 24 is mounted for pivotal movement from the ineffective dotted line position, shown in Fig. 1, where it is out of the paths of the types, to the full line position where it crosses the printing line and extends in the paths of the types. In this last mentioned position the deflector overlaps the forward edge of the deflector 16 and forms virtually a continuation of the channel 19 to aid in quickly and effectively introducing work sheets backwardly beneath the platen into the channel 19.

It is unnecessary, for the purpose of the present invention, to disclose the means by which this deflector 24 is actuated and by which the fine wire line indicator 27 is automatically shifted from the effective, to the ineffective position in Fig. 1, when the deflector 24 is shifted from the dotted to the full-line position and vice versa. It also is unnecessary to disclose herein the means by which these devices are automatically controlled by a shifting of certain of the feed rollers 28 and 29 from the ineffective position shown in Fig. 1 into contact with the platen or a work sheet thereon. Nor is it necessary to disclose the means for automatically lowering the ribbon vibrator from the dotted to the full line position in Fig. 1 when the deflector 24 is moved from ineffective to effective position, thus giving ample clearance between said deflector and vibrator. All of such means are embodied in said hereinbefore mentioned Remington machines.

It will suffice for the purpose of arriving at a better understanding of this invention, in its present embodiment, to bear in mind that the parts referred to operate in the general manner indicated above.

As disclosed in said previously filed applications a set of feed rollers 30 coact only with the work sheet R and its carbon sheet R', whereas one or more additional sets of feed rollers 28 and 29 are employed, depending on the use of the machine as a so-called "two-sheet" biller, or for more than two work sheets. The specific manner of mounting these feed rollers for shifting movement into and out of cooperation with the work sheets with which they coact is disclosed in the hereinbefore referred to Remington machine and need not be specifically described herein.

In accordance with the present invention certain adjustable work sheet gaging means, or paper end-stops, which coact with the bottom edge of a ledger sheet L introduced through the channel 19, as well as certain holding devices, are supported on a detachably mounted auxiliary paper table. These

devices of the present invention and the manner of mounting and adjusting them will now be described.

The detachably mounted auxiliary paper table is designated as a whole by the reference numeral 31 and is provided with backwardly extending flanges 32 at the side edges thereof. The lower edge 33 of the paper table is adapted to fit in a depression 34 extending throughout the length of the upwardly directed rear extension of the deflector 16 formed by off-setting rearwardly the upper portion of said extension. This enables the front face of the paper table to form a continuation of the contact face of the deflector 16. The lower side edge portions of the paper table are adapted to be received between the parallel walls of slots 35 (see Fig. 2) formed between the upper ends of the spacing blocks 17 and 18 and the rearwardly off-set extension of the deflector 16.

Means are provided for adjustably and detachably securing the paper table 31 to the carriage in the position indicated. The adjustable means primarily are provided in order that a table may be properly applied to any of such machines notwithstanding slight variations of the parts in assembling them, etc. The means in question in the present instance, comprise two substantially L-shaped brackets 36. One arm of each of said brackets is provided with two longitudinally extending slots 37 each adapted to receive the stem of a headed clamping screw 38 received at its threaded end in a part of the paper table, as will presently appear. The other arm of each bracket 36 is provided with an arcuate slot 39, the center of which is substantially coincident with the bottom edge 33 of the paper table. This is in order to afford a slight fore and aft adjustment of the paper table around said lower edge as a center and thereby enable the paper table to be properly positioned with reference to the other associated parts. A clamping washer 40 bears on the slotted arm of the associated bracket and is held clamped thereto by a headed clamping screw 41. The stem of each screw 41 passes through its slot 39 and is received at its threaded end in a tapped opening in the upright arm 42 of an angle bracket. Each angle bracket has a foot piece 43 slotted transversely of the machine, as indicated at 44 in Fig. 5. A clamping washer 45 bears against the upper fact of each foot piece 43 and is held in clamping engagement therewith by a nut 46. These nuts are threaded on bolts 47 and by which nuts and bolts the tabulator stop rod 48 ordinarily is secured to the rearwardly extending bracket arms 49 on the carriage. It will be seen that this manner of securing the brackets 42-43 in place enables each of them to be adjusted transversely of the machine to accord with the particular machine to which the paper table is to be

applied, and yet provides for a ready removal of the paper table together with the parts carried thereby as a single unit, when desired.

The paper table carries paper and stops, guides and holding devices as will now be described.

Angle brackets 50 (preferably two in number) are detachably secured by screw bolts and nuts 51 and 52 respectively to the upper rear side of the paper table and project over the upper edge thereof where they provide foot pieces 53 above and forward of the front face of the paper table. To each of said foot pieces is secured by screws 54 a depending paper guiding member or bar 55 which extends parallel with the front face of the paper table and terminates at its lower end before it reaches the looped part 22 of the paper deflector 15. There are preferably two of these guide bars and they may be arranged at suitable points along the paper table and I prefer to make them adjustable lengthwise of the table to different positions depending on the character of the work to be done on the machine. Any suitable means may be provided for this purpose. However, it has been found that the provision of two or more sets of openings 56 in the paper table (see Fig. 6) for the reception of the screw bolts 51 will ordinarily suffice to attain the desired results. This enables each of the supporting brackets 50 and the guide bar carried thereby to be adjusted to two or more positions along the paper table and to be spaced apart at the requisite distances.

It will be seen that the space 57 between each guide bar 55 and the paper table constitutes a continuation of the channel 19 between the two paper deflectors 15 and 16 so that paper introduced backwardly into said channel will pass up between said guide bars and the paper table.

In order to aid in thus guiding the paper, and at the same time cause it to hug the face of the paper table and be held on the table against accidental displacement, I provide each guide bar with spring means which contact with a work sheet introduced as described through the channel 19. In the present instance such means comprises a bent leaf-spring 58 secured at one end, as at 59, to the top side of the associated guide bar. Each spring curves around the lower end of its bar and extends within the outlet of the channel 19, as shown, to provide a curved contact or deflecting face 60. Each spring then continues upwardly and rearwardly in the space 57 between the associated guide bar and paper table, the free end of the spring bearing against the bar or being arranged close thereto. It will be seen that the contact face 60 of each spring slopes towards and makes contact with the paper table so as to direct the rear end of the paper beneath the spring and against the paper table and cause the paper

to be pressed with a light pressure against the face of the paper table. This pressure is insufficient to prevent the comparatively heavy ledger sheet from being introduced 5 rearwardly past the springs but is sufficient to hold the ledger sheet against accidental displacement from its adjusted position when another lighter bill sheet is subsequently introduced in the channel 19. Usually this 10 lighter weight bill sheet is of such depth that it will not extend past the springs 58 when positioned to receive the first line of writing. However, even when the narrower bill sheet is of a depth that carries it beyond the springs 15 58, if the guide bars 55 are beyond the side edges of the bill sheet, then the latter may be introduced rearwardly in the channel 19 without being interfered with by the springs 58 which coact only with the wider ledger sheet. 20 In the present construction I have provided novel paper end-stop devices to coact with the ledger sheet which are carried by and are detachable with the paper table and which I will now describe. 25 A bar 61 of such a thickness that it does not quite fill the space between each guide bar 55 and the paper table passes through such spaces and extends longitudinally of the platen and from end to end of the paper 30 table parallel with the printing line. This bar constitutes an end stop for the rear edge of the ledger sheet L and is mounted and adjusted towards and from the platen on the paper table in the following manner. Referring 35 more particularly to Fig. 7 it will be seen that an angular guide plate 62 is secured by screws 63 to the left-hand end of the stop bar 61 outside of a rack bar 64 riveted at 65, or otherwise secured, to a side flange 32 on the paper table. 40 The rear angular end 66 of the bracket extends back of the associated rack bar 64, thus providing a sliding connection between the stop bar 61 and the paper table. The guide plate 62 is apertured to provide a bearing for a shaft 67. A pinion 68 is fixed on this shaft 45 and meshes with the companion rack bar 64 on the paper table. One end of the shaft 67 is extended at 69 beyond its bearing in the guide plate where it is threaded to coact with a thumb nut 70. The hub of this nut bears 50 against a washer 71 interposed between the hub and the outside of the guide plate 62. The thumb nut 70 when tightened acts as a binding nut to lock the shaft 67 against rotation. 55 On the other hand, when the thumb nut is loosened the shaft is free to be turned. The opposite end of the shaft 67 is mounted in a like manner in a second guide plate 72, as shown in Fig. 6, and carries a second pinion 73 that meshes with a second rack bar 74 secured to the paper table in the same manner as the rack bar 64. To this end of the shaft 67 is secured a knurled head or finger piece 75 by which the shaft may be turned when 60 the nut 70 is loose. From the foregoing it will be understood that the shaft 67 is mounted to travel with the stop bar 61 in the adjustment of the latter and that a turning movement of the finger piece 75 will turn the shaft, if it is free, thereby causing the pinions 68 and 73 to roll along the rack bars 64 and 74 to raise or lower the stop bar, depending on the direction in which the finger piece 75 is turned. It will be understood, moreover, 65 that by this construction the bar is always maintained in parallelism with the printing line, and is always adjustable to a uniform extent at both ends of the bar and that the latter cannot become cramped or stick in its sliding movement of adjustment. When the desired position of adjustment is attained the thumb screw 70 may be tightened and the stop bar will be held firmly in its adjusted position. The upward adjustment of the bar is limited by the pinions 68 and 73 engaging 70 enlarged terminal teeth 76 of the racks 64 and 74 preventing further rotation of the shaft 67 in one direction. The stop bar 61 has a limited downward range of adjustment 75 determined in a like manner by the pinions 73 engaging the full body portions 77 (see Fig. 8) and preventing further rotation of the shaft 67. This point is reached before the stop bar reaches the springs 58. 80 It is sometimes desirable, as when filling 85 in entries near the bottom ends of the ledger sheets, to provide end stops which will reach beyond the range of downward adjustment of the stop bar 61. In order to provide for such a contingency I employ auxiliary end 90 stops somewhat similar to some of those disclosed in the hereinbefore mentioned Burns application, except that in the present construction I employ releasable means by which 95 said stops may be held firmly against accidental displacement from the effective position and also from the ineffective position. Thus, flexible metal arms 78, preferably two 100 in number, are mounted for pivotal movement from an ineffective position on top of the stop bar 61, as shown in full lines in Fig. 6, to an effective position shown in dotted lines. Each of these flexible arms is mounted to turn around the stem of a headed binding screw 79 threaded into the stop bar 61, 105 with a binding washer 80 interposed between the head of the screw and the associated flexible arm. When the screws are loosened the 110 arms may be turned from ineffective to effective positions or vice versa, and a tightening of the screws will firmly clamp the arms against accidental displacement from the positions to which they may be turned. The 115 free end of each flexible arm carries an enlargement 81 of a thickness corresponding 120 substantially to the width of the space between the two walls of the channel 19 and which constitutes an end stop against which the bottom end of a work sheet introduced 125 in the channel 19 may be adjusted, as indi- 130

cated in Fig. 3. It will be understood that when the arms 78 are turned to effective position and the stop bar is adjusted down, say, to the Fig. 3 position, the flexibility of the arms 78 will enable them to bend around the platen and carry the stops 81 in a curvilinear path along the channel 19. In this manner the stops 81 may be brought into use to contact with the bottom edge of a work sheet L when said edge is within the channel 19 and beyond the range of adjustment of the stop bar 61.

The stems of the screws 38 hereinbefore referred to may extend through openings in the flanges 32 on the paper table and take into tapped openings in the rack bars 64 and 74 riveted to said flanges, thus providing a firm connection for the supporting brackets 36 with the paper table.

In the present example, assume that the ledger sheets L are in the nature of printed blanks with separate spaces for various entries thereon, some at least of which are written thereon through an interposed carbon sheet R', or in some instances each bill sheet may have a carbonized back which would answer the same purpose. Also assume that each ledger sheet has printed thereon the months of the year, or the months of more than one year. If, for example, the entries are to be made near the top of each ledger sheet in an appropriate cross line for the month of, say, January, then the operation will be as follows: The first ledger L is introduced rearwardly, as previously described, and accurately positioned with reference to a line finder or indicator 27. When this position has been attained the sheet will be held against accidental displacement by the springs 58 and the end stop 61 is adjusted to coact with the bottom edge of the ledger sheet L, as shown in Fig. 1, and all successive ledger sheets adjusted to said end stop 61 will be accurately positioned to receive the "January" entries. When entries are to be made for the next month, "February", the first sheet will be positioned with the aid of the line indicator 27 and the stop 61 is adjusted as previously described, and all successively introduced ledger sheets L may be quickly and accurately introduced to properly receive entries for that month, and so on for succeeding months.

As entries reach the lower end portion of each ledger sheet L, the lower end thereof is within the channel 19 when properly positioned to receive such entries, and each of such sheets is therefore out of the range of adjustment of the end stop 61. At this time the arms 78 may be swung down into position at right angles to the bar 61, thus bringing the end stops 81 into effective position in advance of the end stop 61. An adjustment of the bar 61 towards or away from the platen is effective at this time to adjust

the end stops 81 along the channel 19 and in a curved path around the platen, as shown in Fig. 3, until the stops coact with the bottom edge of the first ledger sheet L previously positioned with the aid of the line indicator 27.

In this manner entries may be made at as low a point on each ledger sheet as is required, it being understood that a single adjustment of the stops 81 suffices for entering bills during a given month and that the stops 81 operate in the same general manner, and for the same purpose as the end stop 61, but are brought into use when the stop 61 is no longer available to coact with ledger sheets.

In Figs. 8 to 11 inclusive, I have illustrated certain additional features not disclosed in the remaining figures, but which additional features I prefer in practice to employ in conjunction with those represented in Figs. 1 to 7, as will now appear.

I prefer to leave some space between the guide bars 55 and the stop bar 61 in order that the former will not bind against the latter and possibly retard or interfere with the adjustment of the stop bar. This slight space or gap between each guide bar 55 and the stop bar 61, is indicated at 82 in Fig. 10. In practice it sometimes occurs that the bottom edge of a work sheet introduced into the channel 19 will pass up through the gaps 82 between the stop bar 61 and the overlying guide bars 55 and not be arrested against the lower edge of the stop bar 61, as it should be. In order to overcome this difficulty I detachably connect to the top side of the stop bar, with the aid of screws 83, two space-closing blocks or auxiliary end-stop members 84 preferably of a thickness which will bring the top faces of the blocks 84 substantially in alignment with the top sides of the guide bars. One of these blocks 84 is located close to and outside of each of the guide bars 55, thus crossing the slight intervening spaces 82 and forming upstanding end-stops on the bar 61 which prevent the work sheet from entering said intervening spaces 82. The bottom edge of the sheet will therefore be effectively arrested against the bottom edge of the stop bar or the blocks 84 carried thereby.

I have provided two additional sets of tapped openings 85 in the stop bar, one set located near each end thereof. This is in order that the space-closing blocks 84 may be adjusted on the stop bar 61 to accord with the adjustment of each of the guide bars 55 to one or the other of the two sets of openings 85 in the paper table.

The depth of the work sheet to be positioned with the aid of the end-stops is sometimes such that the bottom edges of such sheet when properly positioned, will be below the range of adjustment of the stop bar 61, but will rest on the paper table and not be within the channel 19. Such a condition is repre-

sented in Fig. 8. From a consideration of this view it will be understood that each of the flexible arms 78 is supported in a flat condition on the paper table. The flexibility of

5 the arms at this time may enable the end stops 81 carried thereby to be deflected away from the paper table by a comparatively stiff work sheet, so that the stops will be ineffective to properly arrest and gage the work

10 sheet. In order to overcome this difficulty I employ two comparatively heavy reinforcing leaf-springs or retaining members 86, each mounted for pivotal movement from the

15 full to the dotted line positions in Fig. 9 around the associated binding screw 78 when the latter is loosened. Each reinforcing

20 spring 86 when in the effective full line position bears down against the associated flexible arm 78 and holds it firmly against the

25 paper table where the bottom edge of a work sheet will be arrested by the stop 81, and the latter will be firmly held against accidental displacement by the work sheet. It will

30 be understood that the retaining members or springs 86 are not, and cannot be, employed when the flexible arms 78 are in the channel

35 19 and assume a bent condition. Moreover, the springs 86 are not employed when the stop bar 61 is used to coact directly with work

40 sheets. At such times the springs 86 may be turned to the ineffective position overlying and parallel with the stop bar 61, as indicated in dotted lines in Fig. 9, whether the

45 flexible arms 78 be in the effective or ineffective positions. The springs 86 may be held in ineffective dotted line position, or in the effective position shown in full lines, by

50 tightening the binding screws 79 which act effectively on the retaining springs 86 as well

55 as on the flexible arms 78. It is believed that the representation of the spacing blocks 84 and the retaining springs 86 only in Figs. 8,

60 9, 10 and 11 will avoid confusion in the showing in the remaining figures and contribute

65 to a clearer understanding of the construction, inasmuch as it is only when each of the end stops 81 is adjusted to some such positions as that represented in Figs. 8 and 9 that

70 the retaining springs 86 are brought into use. It should be understood, however, that I prefer to employ these additional devices in

75 connection with those shown in Figs. 1 to 7, as hereinbefore indicated.

When the blocks 84 and springs 86 are employed, the flexible arms will be turned inward and upward from effective to ineffective position, as indicated in Fig. 9, instead of outward and upward to ineffective position, as in Fig. 6.

80 I have hereinbefore indicated that the present machine is capable of a very wide range of use, and may be employed with or without slight change in almost any character of billing or like work wherein two or 85 more sheets are employed, and where one

or more work sheets are introduced into and removed from the machine, while another or other sheets are retained in the machine and a certain correlation is required between the sheet or sheets retained in the machine and those introduced therein from time to time. Therefore the end stops may be employed in a variety of ways.

For example, let it be supposed that the machine is to be used as a check writing machine, in which a copy is to be made of all checks as they are written. In this event the checks only would be rearwardly introduced into the channel 19, the end stops 81 being advanced to some such position as that indicated in Fig. 3 and permitted to remain in such position indefinitely. The record of the checks written would be manifolded through the carbon sheet R' to the record sheet R, both of which latter sheets are fed through the separate channel 20. In this event the sheet R would constitute a "pay-roll" or "register" sheet, the use of the stops 81 in check-writing providing for the adjustment of such stops to accord with checks of different depths.

Generally speaking, the sheet R, if used in bookkeeping work with a ledger sheet, may constitute a so-called "register" or "proof" sheet. If used when copying invoices, it may constitute a "sales" sheet or a "distributing" sheet. If used in check-writing it may constitute a "pay-roll" or "register" sheet. In each event, however, the sheets R and R' remain in the machine while the remaining work sheets L and the bill sheet and accompanying carbon (or either of them as the case may be) are removed after each writing, and new sheets entered in place thereof with the aid of the stop and clamping devices of my invention.

In a companion application filed of even date herewith, Serial No. 172,684, I have included claims which cover features of the present construction; the claims contained herein being restricted to features not disclosed in said companion application.

What I claim as new and desire to secure by Letters Patent, is:—

1. In a typewriting machine, the combination of a platen, a work sheet guide having top and bottom fixed guide walls in the rear of the platen and between which a rearwardly introduced work sheet is guided, and a fixed leaf spring adapted to bear lightly against a work sheet thus introduced and press it against said bottom fixed guide wall without preventing the sheet from passing said leaf spring as the sheet is being introduced as specified into position in the machine, said spring being curved to form a guide surface for directing the sheet between said spring and the bottom fixed guide wall with which it coacts in pressing the sheet.

2. In a typewriting machine, the combination of a platen, means for directing a sheet rearwardly from in front of around and beneath the platen, fixed top and bottom guide walls in the rear of the platen between which a work sheet as it is introduced rearwardly into the machine is guided from said directing means, and a spring pressed element having a contact surface at all times maintained in the space between said guide walls and operative to lightly press a sheet as it is being thus introduced into said space against one of said fixed guide walls and hold the sheet against accidental displacement without preventing the sheet from passing said contact surface as the sheet is being introduced into position in the machine.

3. In a typewriting machine, the combination of a platen, a fixed paper table in the rear of the platen, a depending guide bar secured at one end to and arranged parallel with said paper table, and spring means carried by and fixed to said bar and extending into the space between the bar and the paper table and coacting with a work sheet introduced in said space to press the sheet lightly against the paper table and hold said sheet against accidental displacement without preventing the sheet from passing said spring means as the sheet is being introduced into position in the machine.

4. In a typewriting machine, the combination of a platen, a paper table fixed in the rear of the platen, means for directing a work sheet rearwardly from in front of beneath and around the platen, a depending guide bar secured at its upper end and arranged parallel with said paper table, and spring means carried by and fixed to said bar and extending at all times into the space between the bar and the paper table and coacting with a sheet introduced into said space to press the sheet lightly against the paper table and hold said sheet against accidental displacement without preventing the sheet from passing said spring means as the sheet is being introduced into position in the machine, said spring means having a curved contact face to guide the paper beneath said spring means.

5. In a typewriting machine, the combination of a carriage, a platen carried thereby, two curved paper deflectors arranged one above the other beneath the platen, means for maintaining said deflectors spaced apart so that they with the platen will form two separate channels through which the work sheets may pass, the upper channel being between the platen and the upper deflector, the lower channel being between the two deflectors, a paper table in the rear of the platen, paper guiding means which with said paper table form a continuation of the lower channel, and spring means in said continuation of the lower channel for coacting with a work sheet

therein to press the sheet against the paper table and prevent an accidental displacement of the sheet.

6. In a typewriting machine, the combination of a carriage, a platen carried thereby, two curved paper deflectors arranged one above the other beneath the platen, means for maintaining said deflectors spaced apart so that they with the platen will form two separate channels through which the work sheets may pass, the upper channel being between the platen and the upper deflector, the lower channel being between the two deflectors, a paper table in the rear of the platen, paper guiding means which with said paper table form a continuation of the lower channel, and a curved leaf spring received in said continuation of the lower channel and cooperative with the paper table to hold a work sheet against accidental displacement, a curved surface of said spring acting as a guide to direct paper from the lower channel into said extension and beneath said spring.

7. In a typewriting machine, the combination of a carriage, a platen carried thereby, two curved paper deflectors arranged beneath the platen and maintained spaced apart to form a channel between them, and spring means spaced apart to coact with the side edge portions of a comparatively wide sheet introduced in said channel and hold it against accidental displacement while a narrower sheet may be independently introduced in said channel.

8. In a typewriting machine, the combination of a carriage, a platen carried thereby, two curved paper deflectors arranged beneath the platen and maintained spaced apart to form a channel between them, and a pair of curved leaf springs spaced apart to coact with the side edge portions of a comparatively wide sheet introduced in said channel and hold it against accidental displacement while a narrower sheet may be independently introduced in said channel, curved portions of said springs providing deflecting surfaces for guiding said comparatively wide sheet beneath the springs.

9. In a typewriting machine, the combination of a paper table, a depending guide bar secured at one end and arranged parallel with said paper table, spring means carried by said bar and extending into the space between the bar and the paper table and coacting with a sheet introduced in said space to press the sheet against the paper table and hold said sheet against accidental displacement, and means by which said guide bar may be adjusted to different set positions longitudinally of said paper table.

10. In a typewriting or like machine, the combination of a cylindrical platen, an end stop for the paper, a flexible arm which carries said stop, the flexibility of said arm enabling it to bend to a curved condition which

conforms generally to the curvature of the platen, a pivot on which said arm is mounted for pivotal movement from an ineffective position substantially parallel with the axis of the platen to an effective position around the platen, means for holding the arm in place around the platen in such curved condition, and means rendered effective at will for holding the flexible arm against flexing action.

10 11. In a typewriting or like machine, the combination of a cylindrical platen, an end stop for the paper, a flexible arm which carries said stop, the flexibility of said arm enabling it to bend to a curved condition which conforms generally to the curvature of the platen, a pivot on which said arm is mounted for pivotal movement from an ineffective position substantially parallel with the axis of the platen to an effective position around the platen, means for holding the arm in place around the platen in such curved condition, and spring means which may be shifted into and out of cooperative relation with said flexible arm and which when in cooperative relation with said arm holds it against flexing action.

12. In a typewriting or like machine, the combination of a cylindrical platen, an end stop for the paper, a flexible arm which carries said stop, the flexibility of said arm enabling it to bend to a curved condition which conforms generally to the curvature of the platen, a pivot on which said arm is mounted for pivotal movement from an ineffective position substantially parallel with the axis of the platen to an effective position around the platen, means for holding the arm in place around the platen in such curved condition, and a relatively stiff leaf spring mounted on the same pivot as said flexible arm and shiftable on its pivot into and out of effective position, the spring when in effective position overlying and bearing against the flexible arm and holding it against flexing movement and accidental displacement.

13. In a typewriting or like machine, the combination of a cylindrical platen, an end stop for the paper, a flexible arm which carries said stop, means for adjusting said arm in a curved path around the platen, the flexibility of the arm enabling it to conform generally to the curvature of the platen, and means rendered effective at will to reinforce and prevent a flexing of said arm.

14. In a typewriting machine, the combination of a work sheet guide having top and bottom fixed guide walls between which a work sheet as it is introduced into the machine is guided, and spring means permanently maintained effective against one of said fixed guide walls and adapted to bear against a sheet as it is being thus introduced and lightly press the sheet against one of said fixed walls without preventing the sheet from passing said spring means as the sheet is be-

ing introduced into position in the machine, yet exerting sufficient pressure only on the sheet to hold it against accidental displacement from its adjusted position.

Signed at the borough of Manhattan, city of New York, in the county of New York and State of New York this 2nd day of March A. D. 1927.

FREDERICK A. HART.
